UNITED STATES PATENT OFFICE.

DAVID C. McCAN, OF LOS ANGELES, CALIFORNIA.

FUEL-PRESS.

956,902.

Specification of Letters Patent.

Patented May 3, 1910.

Application filed June 14, 1909. Serial No. 502,148.

To all whom it may concern:

Be it known that I, DAVID C. McCAN, a citizen of the United States, residing at Los Angeles, in the county of Los Angeles and 5 State of California, have invented certain new and useful Improvements in Fuel-Presses, of which the following is a specification.

This invention relates to a fuel press, and 10 has particular reference to a machine for making artificial fuel into blocks or briquets from waste material, such as saw-dust, wood-shavings and the like.

One of the objects of this invention is to 15 provide a machine which will compress a quantity of loose waste material into a solid body, in which all of the strains due to high pressure are centralized and the reactionary effect upon relieving the pressure is offset by 20 the concentration and intimate union of the particles composing the block and the equalization of the inherent strains.

Another object of this invention is to provide a machine for the production of artificial fuel from waste material, which makes 25 the employment of a binder for the molecules of the resultant block unnecessary, and to provide a former for the blocks during 30 the compression of the materials for the same, whereby absolute rigidity and stability of the finished fuel are preserved.

Another object of this invention is to provide in connection with a fuel press, a novel and simple agitator and force feed 35 for the material into the compression chamber, and a simple ejecting mechanism for forcing away from the walls of the mold a finished briquet and causing the discharge of the same therefrom.

With these and other objects in view, this 40 invention consists of the features, details of construction and combination of parts as will be described in connection with the accompanying drawings, and then be more 45 particularly pointed out in the claims.

In the drawings, Figure 1, is an end elevation of the machine. Fig. 2, is a side elevation showing the cam-gear and connected elements for operating the movable mold 50 section. Fig. 3, is a vertical section, showing a briquet in the mold, and the operative positions of the parts of the press. Fig. 4, is a detached plan view, showing the mold, and the toggle connected therewith for operating one section of the mold. Fig. 5, is a

vertical section through the mold, showing the ejectors, and the operating means for the ejectors, the dotted lines indicating the position of the toggle and movable section of the mold when withdrawn. Fig. 6, is a vertical section of the mold showing the inoperative position of the ejector-operating means, and Fig. 7, is a side elevation, showing the mold sections separated, the operative positions of the ejecting plungers, and the operative positions of the means for operating the ejector plungers.

Specifically referring to the drawings, 1, designates a base having mounted thereon two standards, 2 and 3. On said standard 2, is a boss 4, in which is journaled one end of a shaft 5, the other end of which shaft is supported by a standard 6. Mounted on said shaft 5, is a drive pulley 7, and a fly wheel 8. 9 designates a pinion also fixed 75 on said shaft 5, and arranged to mesh with a gear wheel 10 mounted on a crank shaft, which is journaled in the upper ends of the standards 2 and 3. Onto said crank shaft 11, is a connecting rod 12, pivoted to a 80 cross-head 13, which cross-head carries a plunger 14. Said cross-head operates between two guide plates 15 and 16, which are secured to lips or flanges 17, provided on the standards 2 and 3. Secured to the bottom of the said lips 17, is a cup 18, provided with an orifice 19, through which said plunger is arranged to extend and operate. Said cup 18 serves as a wiper for the plunger to remove therefrom all adhering particles of 85 wood shavings and the like, and to prevent the accumulation of such particles in the housing for the cross-head. 20 designates a hopper adapted to receive the loose waste material from a tube 21, provided with an interior or internal feed screw 22, by means of which the material is continually fed under pressure to the hopper. Said hopper 20, is mounted on a plate 23 which is secured to flanges 24 made integral with the standards 100 2 and 3, and is kerfed or rabbeted as seen in Fig. 3, to accommodate the projecting edge 25 of an agitator and force feed 26 mounted within the hopper 20 and seated in a recess 27 provided therefor in the plate 23. To 105 prevent the compaction of wood shavings and like material in the hopper 20 and about the plunger 14, which shavings under pressure readily form a coherent body, I provide in the agitator and force feed 26, a 110

plurality of spiral vanes or ribs 28, which by reason of their acute inclination and the conicity of the agitator, tend to force down any material falling thereto, and also to 5 break up the bulk or solid mass of the material with which the hopper may have become clogged. A belt 29, connected with a pulley 30 made integral with the agitator 26, and with the end of said shaft 5, is 10 arranged to rotate said agitator. To keep the belt or chain in the pulley groove, the rope or chain is extended over a plurality of idlers 31, which are mounted on a boss 32 integral with said hopper 20.

15 The plate 23 is provided with an aperture 33, arranged in register with the compression chamber 34, formed by a mold 35 comprising two sections 36 and 37. The bottom of said chamber formed by the two sections of the mold is rotund and the face of a shoe 38 which is removably fitted into the end of said plunger 14, is likewise concaved for the purpose of causing a centralization of the strains in the fuel block, when the 25 plunger is forced upon the mass of material confined within the compression chamber. The section 37 of said mold is movable, while the section 36 is made fast and rigid with the base 1, and the movement of said 30 movable section is accomplished by the mechanism described as follows: Pivoted to the ears 38' cast integral with a plate 39 which is bolted to said section 37, is a toggle 40 pivoted to a link 41, which is splined or keyed to a shaft 42 journaled in a boss-head 43 provided on the base 1. Fixed to the outside of said shaft 42, is a member 44 pivoted to a sleeve 45 which is loosely and slidably mounted on a rod 46. A collar 47 40 is fixed upon said shaft and in close proximity to said sleeve 45 and this collar is arranged to abut against and force the member 44 and its complementary parts rearwardly, when the rod 46 is actuated. Connected with said sleeve 45 is a helical spring 48 coiled about said rod 46, and held thereon by a nut 49 engaging the screw-threaded extremity 50 of the rod, which nut also serves to regulate the tension of said spring. 45 The function of this spring 48, is to prevent breakage and undue straining of the elements operatively connected therewith, when for any reason the movable section 37 is prevented from fully closing, in which case the 50 rod 46, continues to travel against the tension of the spring carrying with it the collar 47 without affecting the accidentally locked position of the sleeve 45 and its aperturant parts. The rod 46, is connected 55 to one end of a bell-crank 51 pivoted to the outside of the standard 3. Onto the other end of said bell-crank 51, is pivoted a link 52, which carries a roller 53 arranged to operate in the cam groove 54 of a cam gear 55 journaled on the standard 3, and arranged

in mesh with a pinion 56 mounted on the crank shaft 11. 52' designates a strip pivoted to the end of the link 52 carrying the roller 53, and to the standard 3, to hold the roller in the cam-groove 54 and insure the 70 vertical operation of the link 52. This mechanism is clearly shown in Fig. 2. By this arrangement, the plunger operating in the mold or compression chamber, is designed to make two strokes before the cam 75 portion of the cam gear engages the roller, and through such engagement, actuates the rod 46, and eventually the movable section 37 of the mold 35.

75 The liability of the fuel block to adhere to the walls of the compression chamber on account of the great pressure to which it is subjected, would prevent the gradual discharge of the briquet from the mold when the movable section is moved away. To prevent this clinging tendency of the finished fuel block, and to absolutely insure the ejection of the same from the mold chamber, I have provided the following mechanism, shown in Figs. 4, 5, 6, and 7. Extending 80 through the walls of each section of the mold 35, is an ejecting plunger 57, held normally retracted by a helical spring 58 seated in a housing cored in the movable sections 36 and 37. These plungers 57, are provided 85 with heads 59 having projecting lugs 60. On shafts 61, provided one each on and extending transversely of said mold sections, are mounted in operative relation to the lugs 60 on said plunger heads, tangs 62, and on 90 the ends of said shafts are fixed fingers 63 and 63'. Pivoted to said stationary section 36, is a bar 64 provided with a hooked end 65 arranged to engage the finger 63, and pivoted to the movable section 37 is a similar bar 66 arranged in operative relation to the finger 63'. When the sections of the mold are closed, both bars 64 and 66 are held down by pins or studs 67 provided on the sections, as seen in Fig. 6, and which pins 95 100 105 110 115 120 125 130 operate in the cut-away portion 68 of the bars. When the sections begin to open, the flat springs 69, fastened to the sections and exerting upward pressure against the bars 64 and 66, lift the said bars in contact with said pins or studs 67, and bring the hooked ends 65 and 65' thereof in line with the fingers 63 and 63'. As the opening movement of the movable section continues, the hooked ends 65 and 65', engaging the ends of the fingers 63 and 63', cause the tangs 62 to impinge against the plungers 57 and project the same into the mold chamber, thus freeing from the walls thereof the fuel block and allowing it to fall through the discharge opening 70 provided in the base 1, immediately below the movable section 37. Before the complete opening of the movable section has taken place, and after the plungers have been projected to the limit of their

movement, the pins or studs 67, will have ascended the incline 71, in which the cut-away portion of the bars terminate, and dislodged the hooked ends 65 and 65' of the bars from engagement with the finger ends 63 and 63', whereupon the ejecting plungers are returned to their normal positions by the springs 58.

The operation of the machine is substantially as follows:—Assuming that the plunger 14, has completed its first stroke within the mold 35 upon the loose material therein, and is about to be returned preparatory to the second compressive operation, it will be 15 in the position substantially as shown in Fig. 3. In that position, the gear cam 55, receiving power from the pinion 56, will have revolved but for one half its circumference, holding the parts operatively connected therewith inactive. The continued revolution of the driving gear 10, causes a recession of the plunger 14 from the chamber of the mold 35 to a height approximately 20 on a line with the top of the agitator and force feed 26. When the plunger has lifted 25 clear of the orifice in the bottom of the agitator, an additional charge of material is liberated from the compacted mass within the hopper, and this charge falls into the 30 chamber of the mold, while the spiral vanes or ribs 28, aided by the pressure of the continually inflowing supply, force the material into the mold. Upon the second downward movement of the plunger 14, the feed ports to 35 the mold are closed thereby, and the compression of the additional charge upon the first charge, and a further compression of the original charge takes place. When the withdrawal of the plunger from the mold begins, the cam gear 55 will be in the position 40 indicated in Fig. 2. The continued revolution of said cam gear, while the plunger is being withdrawn, causes the roller 53, to engage the cam groove 54, and depress the 45 bell-crank 51, which through its intermediate connections, raises the toggle 40, and withdraws the movable section 37 of the mold. At the same time the hooks 65 and 65', engage the fingers 63 and 63', causing 50 the retraction of the tangs 62, and the projection of the ejecting plungers into the mold chamber, whereupon the fuel block is discharged from the mold. Before the movable section of the mold has completed its 55 rearward travel, the pins or studs 67, will have disengaged the hooks 65 and 65' from the fingers 63 and 63', whereby the reseating of the ejecting plungers is effected. As the cam gear continues to revolve, the cam groove 54 will cause the roller 53 to rise, thereby producing an upward movement of the bell-crank 51, and through its connections, a forward movement of the toggle 40 and the movable section 37 of the mold. The 60 toggle 40 is carried for a small distance be-

yond the dead-center of its joint with the link 41, and in this position of the toggle, the mold section 37, is held absolutely locked during the two compressive movements of the plunger 14.

70

What I claim, is:—

1. In a fuel press, a mold comprising a stationary section and a movable section, a plunger operating in said mold, and means to move said movable section in one direction to discharge the contents of said mold, and in the opposite direction to close the compression chamber previous to the complete recession of said plunger from the compression chamber.

80

2. In a fuel press, a mold comprising a stationary section and a movable section, said mold having a dome-shaped bottom, a plunger operating in said mold and provided with a dome-shaped shoe, a conical agitator and force feed communicating with the interior of said mold, means to operate said agitator, means to move said movable section upon the recession of the plunger, ejecting means carried by said mold and operable by the movement thereof in one direction, and means to operate said moving means.

85

3. In a fuel press, the combination with a base and standards mounted thereon, said base being provided with a discharge opening, of a sectional mold on said base, said mold having a dome-shaped bottom, a plunger provided with a dome-shaped shoe and arranged to operate in said mold, geared means to operate said plunger, a rotatory force feed above said mold, an ejecting mechanism connected with said mold, and a geared cam to move one section of said mold and actuate said ejecting means to cause a discharge of the contents of the mold through the discharge opening in said base.

95

4. In a fuel block machine, the combination with a base having a discharge opening and a plurality of standards mounted on said base, of a sectional mold on said base, a hopper, a feed therefor, a rotating agitator between said hopper and said mold, a plunger arranged to operate in said mold, geared means journaled in said standards to actuate said plunger, an ejecting mechanism connected with said mold, and means to move one section of said mold in one direction to operate said ejecting mechanism and discharge a fuel block through the discharge opening in said base, said means also being arranged to move said section in the opposite direction previous to the recession of the plunger from the mold, and to hold said section locked during the compression stroke of the plunger in the mold.

100

5. In a fuel press, a sectional mold, a plunger operating therein, an ejecting plunger in each section of said mold, means on said mold to operate and trip said ejecting

115

120

125

130

- plungers, and means to move one section of said mold to control both said ejecting plungers.
6. In a fuel press, a mold comprising a stationary section and a movable section, a plunger operating in said mold, an ejector in each section of said mold, means to operate said ejectors, a rod on each section of said mold arranged to operate said ejector operating means, and means to move said movable section to control said rods.
7. In a fuel press, a mold comprising a stationary section and a movable section, a plunger operating in said mold, means to operate said plunger, an ejector in each section of said mold, means to hold said ejectors normally retracted, a shaft journaled on each section of said mold, tangs on said shafts and in operative relation to said ejectors, a plurality of fingers on said shafts, a rod on each section of said mold and in operative relation to said fingers, means to move said movable section to cause said rods to engage said fingers and operate said ejectors and means to trip said rods to cause a return of said plungers to normal position.
8. In a fuel press, a mold comprising a stationary section and a movable section, a plunger operating in said mold, an ejector in each section of said mold, means to hold said ejectors normally retracted, shafts provided in said sections, tangs mounted thereon and in operative relation to said ejectors, fingers carried by said shafts, means pivoted to said sections to operate said fingers and ejectors, and means to move said movable section to control said finger-operating means.
9. In a fuel press, a mold comprising a stationary section and a movable section, a plunger operating in said mold, a normally inoperative ejector housed in each section of said mold, means to operate said ejectors, a rod on each section of said mold to operate said ejector operating means, means to move said movable section to control said rods, and means to trip said rods from engagement with said ejector operating means at the end of the movement of said movable section in one direction.
10. In a fuel press, the combination with a base, and standards mounted thereon, of a drive shaft, a support therefor a spur gear on said shaft, a crank-shaft mounted on said standards, a gear wheel on said crank-shaft and in mesh with said spur gear, a plunger carried by said crank-shaft, a sectional mold on said base, an agitator and force feed above said mold, means connected with said drive shaft to rotate said agitator, a cam gear on one of said standards, a pinion on said crank shaft arranged in mesh with said cam gear, and means connected with said cam gear and one section of said mold to open and close said section.
11. In a fuel press, the combination with a base, and a plurality of standards mounted thereon, of a crank shaft journaled in said standards, means to operate said crank shaft, a plunger on said crank-shaft, a sectional mold in which said plunger is arranged to operate, an ejecting mechanism connected with said mold, trunnions on said base, a shaft journaled in said trunnions, a link on said shaft, a toggle pivoted to said link and one section of said mold, a cam gear on one of said standards a gear wheel on said crank-shaft to operate said cam gear, and means connected with said cam gear and shaft and operable by the revolution of said cam gear to open and close one section of said mold and thereby control said ejecting mechanism.
12. In a fuel press, the combination with a base and a plurality of standards mounted thereon, of a crank shaft journaled in said standards, means to operate said crank shaft, a plunger carried by said crank-shaft, a sectional mold in which said plunger is arranged to operate, an ejecting mechanism connected with said mold, trunnions on said base, a shaft journaled in said trunnions, a link on said shaft, a toggle pivoted to said link, and one section of said mold, a cam gear on one of said standards, a gear wheel on said crank shaft to operate said cam gear, a bell crank pivoted to one of said standards, means pivoted to one end of said bell crank to operate said toggle and one section of said mold, and means connected with the other end of said bell-crank and said cam gear to operate said bell-crank.
13. In a fuel press, the combination with a base and standards mounted thereon, of a sectional mold mounted on said base, a rotatory agitator for said mold, means to operate said agitator, a plunger operating in said mold, means to operate said plunger, and means to move one section of said mold at the end of each second stroke of said plunger, said means comprising a toggle, an operating shaft therefor, a rod, a sleeve on said rod, a member on said shaft and pivoted to said sleeve, a collar on said rod to operate said sleeve, a buffer carried by said rod, a bell crank mounted on one of said standards to actuate said rod, a gear cam to actuate said bell crank, and means to operate said bell crank.
14. In a fuel press, a mold comprising a stationary and a movable section, said mold having a dome-shaped bottom, a plunger operating therein and provided with a dome-shaped shoe, a conical agitator above said mold, said agitator being provided with spiral vanes to force material to said mold, means to rotate said agitator, an ejector in each section of said mold, shafts on each section of said mold, tangs on said shafts and in operative relation to said ejectors, and means to move said movable section of

said mold upon the recession of said plunger therefrom to actuate said ejectors.

15. In a fuel press, a mold comprising a stationary section and a movable section, 5 said mold having a dome-shaped bottom, a plunger operating therein and provided with a dome-shaped shoe, a conical agitator above said mold, said agitator being provided with spiral vanes to force material to said mold, 10 means to rotate said agitator, an ejector extending through each section of said mold, shafts on each section of said mold, tangs on said shafts and in operative relation to said ejectors, fingers on the ends of said shafts,

bars pivoted to the sections of said mold and 15 provided with hooked ends arranged in line with the ends of said fingers, means to move one section of said mold to cause said bars to engage said fingers and actuate said ejectors, and means to trip said bars from engagement with said fingers. 20

In testimony whereof, I affix my signature in the presence of two witnesses.

DAVID C. McCAN.
